FOREIGN PATENT DOCUMENTS

JP 2013240723 A 12/2013

Primary Examiner — Cathron C Brooks

(74) Attorney, Agent, or Firm — Gardner Groff
Greenwald & Villanueva, PC(57) **CLAIM**

The ornamental design for a bassinet, substantially as shown and described.

DESCRIPTION

FIG. 1 is a top perspective view of a bassinet, according to an example embodiment of the design;

FIG. 2 is a front view of the bassinet of FIG. 1;

FIG. 3 is a rear view of the bassinet of FIG. 1;

FIG. 4 is a right side view of the bassinet of FIG. 1, the left side view being a mirror image thereof;

FIG. 5 is a top view of the bassinet of FIG. 1; and,

FIG. 6 is a bottom view of the bassinet of FIG. 1.

The broken lines shown in the drawings illustrate portions of the bassinet that form no part of the claimed design.
